UNITED STATES PATENT OFFICE.

MATTHEW T. CHAPMAN, OF AURORA, ILLINOIS, ASSIGNOR TO THE AMERICAN WELL WORKS, OF AURORA, ILLINOIS, A CORPORATION OF ILLINOIS.

WELL-SINKING APPARATUS.

1,079,396.

Specification of Letters Patent. Patented Nov. 25, 1913.

Application filed May 16, 1910. Serial No. 561,596.

To all whom it may concern:

Be it known that I, MATTHEW T. CHAPMAN, a citizen of the United States, residing at Aurora, in the county of Kane and State of Illinois, have invented certain new and useful Improvements in Well-Sinking Apparatus, of which the following is a specification, reference being had to the accompanying drawings.

10 My invention relates to apparatus for boring wells, and has for its object to provide certain improvements in the mechanism employed for gripping and rotating the pipe in the various operations that must be performed, such as rotating the pipe for boring the well, and for supporting sections of the pipe in coupling or disconnecting the sections.

20 My improvements relate more particularly to the construction of the turntable which carries the pipe gripping and supporting devices; to the devices for engaging the pipe so as to hold it against rotation, as is necessary when one section is being coupled to another; to the mechanism for gripping the pipe for rotating it either in boring the well or when one section is being connected to or disconnected from another; and to mechanism for supporting the pipe as 30 occasion may require.

I accomplish my object as illustrated in the drawings and as hereinafter described.

What I regard as new is set forth in the claims.

35 In the accompanying drawings, Figure 1 is a side elevation, some parts being broken away; Fig. 2 is a plan view of the turntable, some parts being in section, and the cover-plate being removed; Fig. 3 is a view of the gripping mechanism taken substantially on line 3—3 of Fig. 1; Fig. 4 is an enlarged detail, being a partial horizontal sectional view showing the construction of the gripping mechanism; Fig. 5 is an edge view of one of the swinging arms or members of the gripping mechanism; Fig. 6 is an enlarged sectional view of a part of the gripping mechanism taken on line 6—6 of Fig. 4; Fig. 7 is a face view of the parts shown in Fig. 6; Fig. 8 is a partial sectional view taken on line 8—8 of Fig. 1; Fig. 9 is a side view of the parts shown in Fig. 8; Fig. 10 is a section on line 10—10 of Fig. 8; Fig. 11 is an enlarged detail, being a partial vertical section showing one of the devices for grip-

ping one of the pipe couplings; Fig. 12 is a plan view, partly in section, of the parts shown in Fig. 11; Fig. 13 is an enlarged detail, being a partial vertical section of the gripping devices for holding the well-tube or pipe against rotation; Fig. 14 is a plan view, partly in section, of the parts shown in Fig. 13; Fig. 15 is a partial vertical section of the upper portion of the turntable, being substantially a section on line 15—15 of Fig. 16; Fig. 16 is a partial plan view of the parts shown in Fig. 15; and Fig. 17 is an enlarged detail, being a partial horizontal section of one of the gripping members, showing the arrangement for adapting the gripping devices to fit pipe of different sizes.

Referring to the drawings, 18 indicates the bed-plate or base of the turntable, which is preferably mounted on a suitable frame or support 19 and is provided with an upwardly-extending annular sleeve 20, as best shown in Fig. 1. Said sleeve is provided at its upper edge with a series of notches 21 arranged at suitable intervals, which are adapted to receive downwardly-projecting lugs 22 carried by a cover-plate 23 which is adapted to fit upon the upper edge of the sleeve 20, as best shown in Fig. 15. By this construction the cover-plate 23 is held fixedly against rotation. Said cover-plate is provided at the center with a circular opening 24 for the passage of the well-tube or pipe, and around said opening at intervals are pairs of lugs 25, thereby providing notches 26 for holding the pipe against rotation, as hereinafter described. The cover-plate 23 is removable, so that if desired cover-plates having different sized openings 24 may be employed with well-tubes of different sizes. The bed-plate 18 with the sleeve 20 and cover-plate 23 constitute the stationary member of the turntable. The rotary member of the turntable is composed of a vertically-disposed sleeve 27 which fits around the outside of the sleeve 20 and is provided at its lower edge with a flange 28 which forms an annular bearing for conical anti-friction rollers 29, as shown in Fig. 1. Said rollers are placed in an annular runway 30 provided on the bed-plate 18, as shown, and they are held in place by an upwardly-extending flange 31 carried by the bed-plate and a downwardly-extending flange 32 carried by the flange 28, as best shown in Fig. 116

1. The rotary member 27 is held down by a series of rollers 33 carried by lugs 34 rising from the bed-plate and bearing on the upper surface of the flange 28 which is suitably shaped to form a track for said rollers. Any desired number of rollers 33 may be employed, but I prefer to provide four, as shown in Fig. 2. The rotary member 27 is caused to rotate by means of an annular 5 rack 35 provided near its upper margin, said rack being engaged by a pinion 36 mounted on a drive-shaft 37, said shaft having a bearing in a standard 38, as shown in Fig. 10. Obviously, by rotating the shaft 37 the 15 rotary member 27 will be caused to rotate, traveling upon the rollers 29. By mounting the rotary member outside of the stationary member in the manner described, it is prevented from being accidentally displaced, 20 and, moreover, the central opening for the passage of the pipe may be made much larger than in former constructions.

39 40 indicate upright posts carried at opposite sides of the rotary member 27, which 25 posts carry the devices for gripping the well-tube, as hereinafter described.

41 42 indicate lower and upper sections of the well-tube, which are united by a screw-threaded coupling 43, as shown in 30 Fig. 1.

44 indicates a clamp for supporting the well-tube when connecting or disconnecting two sections thereof and for holding the lower section against rotation in either direction. Said clamp is composed of two members hinged together at one side by a pivot 45 and adapted to be secured together at the other side by a latch in the form of a swinging link 46, which is mounted in and 35 embraces lugs 47, 48 projecting from the two members of the clamp, as described and claimed in my pending application Serial No. 483,264, filed March 13, 1909. The interior diameter of the clamp 44 is substantially the same as the exterior diameter of 40 the well-tube, so that when said clamp is secured upon the well-tube below the coupling 43 it is adapted to rest upon the cover-plate 23 and support the well-tube. For the purpose of locking the clamp 44 against rotation when resting on said cover-plate, it is 45 provided at opposite sides with depending lugs 49 which fit in the notches formed by the lugs 25 rising from the cover-plate, as 50 shown in Figs. 1 and 10. Thus the clamp 44 is held fixedly against rotation, but may readily be disconnected from the cover-plate when desired by lifting the well-tube 55 slightly. In order to hold the well-tube against rotation in either direction when the clamp 44 is in position thereon, the members of said clamp are provided with gripping disks 50, preferably arranged in pairs, one above another, as shown in Figs. 10 and 60 65 13. Said disks are flat, except that at the

opposite sides of the centers thereof they are provided with bosses 51, as best shown in Fig. 14. The edges of the disks are sharp and they are made of hardened steel, so that they are adapted to bite into the well-tube when they engage the same angularly. Said disks are mounted in suitable pockets 52 provided to receive them, the outer walls of said pockets being inclined downward and inward so that the disks 50, when placed in 70 said pockets, are naturally thrown into engagement with the well-tube. The inner edges of said pockets are provided with inwardly-projecting flanges 53 adapted to engage the bosses 51 and prevent the disks 75 from falling out of the pockets when the clamp is removed from the well-tube. Preferably the two disks 50 are of different diameters, the smaller one being fitted in the lower portion of the pocket where it is shallower, as shown in Fig. 13. It will be 80 apparent that gravity will operate to normally hold the disks 50 in engagement with the well-tube when the clamp 44 is in place thereon, and that any attempt to rotate the well-tube will deflect the disks laterally so as to cause one or the other of their edges to engage the well-tube and bite into it, thereby holding it against rotation. In order to release the well-tube and permit of its rotation when desired, rocking levers 54 are provided in the pockets 52, said levers extending under the several disks, as shown in Fig. 13, so that by depressing any given lever 90 the disk overlying it may be lifted and moved out of engagement with the well-tube. 95

In order to hold the coupling 43 against rotation when desired, I have provided the clamp 44 with similar devices for engaging it and holding it, 55 indicating a tapered pocket adapted to receive a disk 56 similar to the disks 50. The pockets 55 are placed higher up and are set farther out than the pockets 52, as best shown in Fig. 11, and consequently they are in a position to engage the coupling 43. Preferably two of each of the pockets 52 and 55 are provided, as shown in Fig. 8. Each of the pockets 55 is also provided with a lever 57 by which the disk 56 may be moved out of engagement 100 with the coupling 43. 105

58 indicates lugs projecting at opposite sides of the clamp 44, said lugs being preferably in the form of eyes which may be engaged by hoisting mechanism for lifting the 110 clamp and well-tube.

For the purpose of rotating the well-tube in sinking the well or for rotating the upper section 42 of the well-tube in connecting or disconnecting sections thereof, I employ 115 gripping mechanism which will now be described. 59 60 indicate coacting gripping-levers, which are in part semi-circular in form and are pivotally mounted upon the posts 39, 40, as best shown in Figs. 1 and 3. 120 125 130

Said levers are adapted to slide longitudinally of their respective posts, and in order to control the freedom with which they slide thereon I provide brakes 61 which are fitted in suitable boxes 62 with which said levers are provided and are adapted to bear against their respective posts, as shown in Fig. 4. The brakes 61 may be pressed against their respective posts by screws 63 fitted in said boxes 62, as shown in Fig. 4, so that if desired the levers 59 60 may be permitted to slide freely upon the posts or may be secured thereon so that they do not slide at all. Each of the brakes 61 comprises a brake-shoe 64 adapted to bear on the post, a rubber block or cushion 65 which bears against the shoe, and a plate 66 interposed between said cushion and the end of the screw 59, thus providing a degree of flexibility in the action of the brake. 67 indicates a handle for rotating the screw 63. The two levers 59 60, when in operative position, extend at opposite sides of the well-tube and are connected together by swinging bolts 68 69, the bolt 68 being pivoted to the lever 60 near the post 39 and being adapted to fit in a slot provided in the outer end of the lever 59, while the bolt 69 is pivoted in a corresponding post on the lever 59 and enters a slot in the end of the lever 60, as clearly shown in Figs. 3 and 4. Said slots are indicated in Fig. 4 by the number 70. Each of the bolts 68 69 is provided with a nut 71 which bears against the outer end of the lever which the free end of said bolt engages, as shown in Fig. 4. By adjusting the nuts 71 upon their respective bolts, the levers 59 60 may be caused to clamp the well-tube more or less tightly, as desired. Each of the levers 59 60 is channeled, being composed of a vertical web 72 and upper and lower inwardly-projecting flanges 73 74, as shown in Fig. 6. The curved portions of said flanges 73 74 are provided with serrations or teeth 75, as shown in Figs. 4 and 5, for better securing the gripping devices thereto, as hereinafter described. 76 indicates gripping heads which carry teeth 77 which engage and bite into the well-tube to hold it against rotation, as hereinafter described. Said heads 76 are in the form of blocks of steel, or other suitable material, the outer surface of which is provided with serrated portions 78 adapted to engage the serrations 75 of the levers 59 60. Said heads fit against the inner faces of the flanges 73 74 between overlapping lips 79 80, as shown in Fig. 6, and are held in position by bolts 81 which are adjustably secured in slots 82 in the levers 59 60, as shown in Figs. 4 and 6. The heads 76 are provided with suitable grooves to receive the teeth 77, which are short lengths of steel either square, triangular or otherwise angular in cross-section, and are held

so as to present one edge thereof to the well-tube and in such position that such edge extends longitudinally thereof. Preferably each head carries four teeth 77, said teeth being arranged in upper and lower pairs held apart by the head 83 of the bolt 81, and when the head 76 is in operative position the lips 79 80 project beyond the outer ends of said teeth and prevent displacement thereof in an outward direction. Any desired number of heads 76 may be employed, and the number of teeth carried by each head may, of course, be varied. Furthermore, the position of the several heads with respect to each other may be varied, as the heads may be adjusted upon their respective levers to move them closer together or farther apart.

For operating upon small sizes of pipe, it may be necessary to set the heads 76 farther from the inner faces of the levers 59 60 than in the construction shown in Figs. 3 and 4, and in order to provide for the use of my improved apparatus on even the smallest sizes of pipe I employ a series of auxiliary heads or blocks 84, which are best shown in Fig. 17. Said blocks are segmental and are provided with serrations on both broad faces, so that they may be interposed between the head 76 and the flanges 73 74 of the gripping levers in the manner shown in Fig. 17. Thus the head 76 may be set as far in as may be necessary to secure a proper grip upon the well-tube. In order to remove the gripping levers from the well-tube, it is necessary only to release one or both of the bolts 68 69, and by adjusting such bolts the force with which the well-tube is gripped may be regulated at pleasure.

My invention is not restricted to the construction shown and described, except in so far as it is particularly claimed, but includes generically the subject-matter of the broader claims.

That which I claim as my invention, and desire to secure by Letters Patent, is—

1. In a well-sinking apparatus, the combination of a base having an upright annular sleeve, a turntable mounted on the base, a detachable cover-plate mounted upon and non-rotatably engaging said sleeve, a clamp adapted to embrace the well-tube and adapted to non-rotatably engage the cover-plate, and means carried by said clamp for holding the well-tube against rotation.

2. In a well-sinking apparatus, the combination of a base having an upright annular sleeve, a turntable mounted on the base, a detachable cover-plate mounted upon and non-rotatably engaging said sleeve, said cover-plate having notches in its upper surface, a clamp adapted to embrace the well-tube and having means adapted to engage said notches to hold said clamp non-rotata-

bly in engagement with said cover-plate, and means carried by said clamp for holding the well-tube against rotation.

3. In a well-sinking apparatus, the combination of a stationary base, a clamp adapted to embrace the well-tube, means non-rotatably connecting said clamp with said base, gripping devices carried by said clamp at different distances from the axis of the well-tube for engaging the well-tube and a coupling thereof for holding the same against rotation.

4. In a well-sinking apparatus, the combination of a stationary base, a clamp adapted to embrace the well-tube, means non-rotatably connecting said clamp with said base, gripping devices carried by said clamp at different distances from the axis of the well-tube for engaging the well-tube and a coupling thereof, for holding the same against rotation, a turntable mounted on said base, and means carried by the turntable for engaging and gripping the well-tube for rotating the same.

5. In a well-sinking apparatus, the combination of a stationary base, a clamp adapted to embrace the well-tube, means non-rotatably connecting said clamp with said base, gripping devices carried by said clamp at different distances from the axis of the well-tube for engaging the well-tube and a coupling thereof for holding the same against rotation, a turntable mounted on said base, and vertically-movable means carried by the turntable for engaging and rotating the well-tube.

6. In a well-sinking apparatus, the combination of a stationary base, a clamp adapted to embrace the well-tube, means non-rotatably connecting said clamp with said base, gripping devices carried by said clamp at different distances from the axis of the well-tube for engaging the well-tube and a coupling thereof for holding the same against rotation, a turntable mounted on said base, upright posts carried by the turntable, and gripping mechanism for gripping the well-tube for rotating the same, said gripping mechanism being mounted on said posts and movable longitudinally thereof.

7. A gripping device for non-rotatably engaging a tube, comprising a suitable support adapted to embrace the tube, said support having one or more pockets open toward the tube, and one or more disks loosely fitted in said pockets and having one or more sharp edges adapted to engage the tube and grip the same.

8. A gripping device for non-rotatably engaging a tube, comprising a suitable support adapted to embrace the tube, said support having one or more pockets open toward the tube, and one or more disks loosely fitted in said pockets and having one or more sharp edges adapted to engage the

tube and grip the same, the wall of said pocket opposite said opening being inclined inward and downward.

9. A gripping device for non-rotatably engaging a tube, comprising a suitable support adapted to embrace the tube, said support having one or more pockets open toward the tube, one or more disks loosely fitted in said pockets and having one or more sharp edges adapted to engage the tube and grip the same, the wall of said pocket opposite said opening being inclined inward and downward, bosses carried at the sides of said disks, and means carried by said pockets for engaging said bosses to prevent said disks from escaping from said pockets.

10. A gripping device for non-rotatably engaging a tube, comprising a suitable support adapted to embrace the tube, said support having one or more pockets open toward the tube, one or more disks loosely fitted in said pockets and having one or more sharp edges adapted to engage the tube and grip the same, and means for lifting said disks out of operative position.

11. A gripping device for non-rotatably engaging a tube, comprising a suitable support adapted to embrace the tube, said support having one or more pockets open toward the tube, one or more disks loosely fitted in said pockets and having one or more sharp edges adapted to engage the tube and grip the same, and a lever for lifting said disks out of operative position.

12. A gripping device for non-rotatably engaging a tube, comprising a support adapted to embrace a tube, said support having one or more pockets open toward the tube, and a plurality of disks mounted one above another in said pockets and adapted to engage the tube, said disks having one or more sharp edges adapted to grip the tube.

13. A gripping device for non-rotatably engaging a tube, comprising a support adapted to embrace a tube, said support having one or more pockets open toward the tube, a plurality of disks mounted one above another in said pockets and adapted to engage the tube, said disks having one or more sharp edges adapted to grip the tube, and means for lifting said disks out of operative position.

14. A gripping device for non-rotatably engaging a tube, comprising a support adapted to embrace a tube, said support having one or more pockets open toward the tube, a plurality of disks mounted one above another in said pockets and adapted to engage the tube, said disks having one or more sharp edges adapted to grip the tube, and levers for lifting said disks out of operative position.

15. A gripping device for non-rotatably engaging a tube, comprising a hinged clamp adapted to embrace the tube, said clamp hav-

ing one or more pockets open toward the tube, and one or more disks loosely fitted in said pockets and having one or more sharp edges adapted to engage the tube and grip the same.

16. A gripping device for well-tubes, comprising a clamp adapted to embrace the well-tube below one of the couplings thereof, and gripping means carried by said clamp at different heights and at different distances from the center thereof whereby said gripping devices are adapted to grip the well-tube and the coupling.

17. A gripping device for well-tubes, comprising a clamp adapted to embrace the well-tube below one of the couplings thereof, pockets carried by the clamp at different heights and at different distances from the center thereof, and disks loosely mounted in said pockets and adapted to engage and grip the well-tube and the coupling thereof.
